C. K. VOLCKENING

DUST CATCHER FOR RADIATORS

Filed Nov. 27, 1925

INVENTOR
Charles K. Volckenring

BY Walton Harrison.

ATTORNEY

UNITED STATES PATENT OFFICE.

CHARLES KASPER VOLCKENING, OF BROOKLYN, NEW YORK.

DUST CATCHER FOR RADIATORS.

Application filed November 27, 1925. Serial No. 71,853.

My invention relates to dust catchers for radiators; that is, to devices used in connection with radiators of the type used for heating buildings and the like, for settling and holding particles of dust and smoke, in order to facilitate their removal from the air circulating about the radiator.

More particularly stated, I seek to produce a dust catcher specially adapted for use with ordinary household radiators and the casings customarily employed with such radiators, my device having provision for facilitating the dislodgement and removal of dust and dirt after the separation thereof from the air.

More particularly stated, I provide a textile fabric upon which the particles of dust and smoke are settled automatically and retained by the fabric, after which the fabric is cleaned and restored to duty.

My improved dust catcher is preferably mounted within and carried by a casing, in which the radiator is housed.

Reference is made to the accompanying drawings forming a part of this specification and in which like reference characters indicate like parts throughout the several figures.

Figure 1 is partly a front elevation and partly a vertical section of my improved dust catcher.

Figure 2 is a section on the line 2—2 of Figure 1, looking in the direction indicated by the arrows.

Figure 3 is an end elevation of the device.

A radiator is shown at 4, and is provided with legs 5 upon which it is supported. Connected with the radiator is a steam or hot water fixture 6 controllable by a hand valve 7 in the usual manner.

A casing 8, made of metal or other material capable of withstanding a moderate degree of heat, is provided and used as a housing for the radiator. The purpose of the casing is to prevent smoke and dust, carried by the air as it circulates around the radiator, from settling upon walls, curtains, furniture, and the like, in immediate proximity to the radiator.

As is well known in this art, practically all objects located close to a radiator soon become soiled or blackened by particles of smoke and dust, unless the radiator is enclosed in a casing.

The casing 8 is provided with a back wall 9 and a front wall 10, the back wall being free from openings and disposed at the back

of the radiator, or in other words, between the radiator and the adjacent wall of the room. The front wall of the radiator is provided with openings 11 to allow the escape of hot air which circulates in consequence of the heating of the radiator. These openings 11 are so arranged as to discharge hot air, laden, of course, with the particles of smoke and dust as aforesaid, out into the open space of the room where the radiator is located.

Up to this point, the construction of the radiator and casing may be of the type heretofore used.

The walls 9 and 10 of the radiator are each cut away at the bottom, which is thereby provided with an edge 12, located a little distance above the floor. The casing is provided with end walls 13 and 14, which are slightly cut away at the sides, as may be understood from Figures 2 and 3.

Extending lengthwise through the casing, and supported by the end walls 13 and 14 thereof, are a pair of revoluble shafts 15 and 16, and partially wound upon these two shafts is a lengthy web 17, in the form of a textile fabric. This textile fabric may be cheese cloth, mosquito netting of small mesh, sleazy cloth, or in fact almost any sort of textile material through which air can circulate rather freely, and which is capable of holding particles of dust or smoke which settle upon it and lodge throughout its substance, as the air passes through it. The textile fabric 17, being wound upon the revoluble shafts 15 and 16, is thereby formed into rolls 18 and 19, as indicated more particularly in Figure 2.

Extending through the casing and supported by the end walls thereof are guide rods 20, 21, 22 and 23, made of metal such as steel, and which are preferably smooth. The two guide rods 20 and 21 are located in close proximity to the back wall 9, but the guide rods 22 and 23 are spaced a little distance from the front wall 10, adjacent which they are located. The web of textile fabric, partially wound upon the shaft 15 and thus formed into the roll 18 as above described, extends therefrom obliquely upward to the right according to Figure 2, thus engaging the rod 20, thence extending straight upwardly into engagement with the rod 21, thence across the top of the radiator and into engagement with the rod 22, thence extending straight downwardly and engag-

ing the rod 23, thence extending obliquely downward and formed into the roll 19 carried by the shaft 16.

The shafts 20, 21, 22 and 23 are fitted at 5 their ends with nuts 24 for holding them in position.

The two revoluble shafts 15 and 16 are provided with end portions 25, 26, which are squared or rendered angular as indicated in 10 Figures 1 and 3.

I provide a winding crank 27 of the form indicated in Figure 3, and this winding crank can be detachably fitted upon the end portion 25 or 26, and turned by hand so as 15 to cause the shaft to revolve.

By placing the winding crank 27 upon the angular end 26 of the shaft 16, and turning to the left according to Figure 2, the shaft 16 is rotated in a counter-clockwise direction according to this figure. By detaching the winding crank and fitting it upon the angular end portion 25 of the shaft 15, this shaft may be turned in a clockwise direction according to Figure 2.

25 Thus the web 17 of textile material is wound back and forth as desired by the operator.

The web may be removed from the casing in any desired manner, but preferably by 30 simply unwinding it from the revoluble shafts 15 and 16. Thus removed, it can be cleaned and replaced.

The web, when removed from the casing, may be cleaned by washing, brushing, or by 35 use of a vacuum cleaner, or even by hanging it out in the wind for a few hours.

The operation of my device is as follows:

The various parts being arranged and assembled the operator turns one of the 40 revoluble shafts, say the one numbered 16, and turns it in a clockwise direction according to Figure 2 until the roll 18 becomes pretty large and the roll 19 relatively small.

The radiator being in action, its heat 45 causes the air around it to flow upwardly within the casing, and to make its escape by passing through the openings 11 and the portion of the web 17 stretched between the rods 22 and 23, as indicated at the left of 50 Figure 2. Any particles of dust or smoke, present in the air thus circulated, lodge upon the said portion of the web stretched between the rods 22 and 23 and are thus sifted out, and confined upon the surface of 55 the web, or lodged within its substance. Thus the air passing from the radiator out into the room, is freed of its particles of dust and smoke, and rendered in good condition for breathing.

60 As may be seen from the foregoing description, my invention tends to prevent the deposit of dust and smoke upon curtains, walls of the room, furniture and the like, and at the same time renders the air suitable for breathing.

After one portion of the web is soiled and blackened by the dust and smoke passing through it, the web is shifted as above described, so as to wind up the portion thus affected, and to leave exposed another portion stretched between the rods 22 and 23.

Within reasonable limits the web may be of any desired length, and depending upon its length relatively to the size of the radiator casing, may be shifted once, twice, or even a larger number of times, in the same direction. This means that the web is exposed step by step to the action of the dust and smoke, until practically all portions of the web have become dirty, and the web requires cleaning.

I do not limit myself to the precise construction shown, as variations may be made therein without departing from my invention, the spirit of which is commensurate 85 with my claims.

Having thus described my invention, what I claim as new and desire to secure by Letters Patent is as follows:

1. A device of the character described, 90 comprising a radiator casing for fitting over a radiator and provided with openings through which air can escape when circulated by the heat of said radiator, a plurality of rods carried by said casing and extending 95 through said casing and in proximity to the radiator, a member of textile fabric engaging said rods and partially supported thereby, said member of textile fabric being of a texture suitable for arresting and retaining particles of dust and smoke, and mechanism connected with said casing and with 100 said member of textile fabric and manually operable for shifting said member of textile fabric into different positions.

2. A device of the character described, 105 comprising a radiator casing provided with openings to facilitate the passage of air from the radiator out into the room, a cloth member connected with said radiator casing and so located that air in passing through said openings passes also through said cloth, and mechanism connected with said cloth and manually operable for shifting said cloth 110 into different positions relative to the openings in said radiator casing.

3. A device of the character described, 115 comprising a radiator casing provided with openings through which air heated by the radiator can escape, a flexible member made of textile fabric and having a portion spread out in proximity to said openings in order to arrest and retain particles of dust and smoke and thus to prevent them from 120 passing out through said openings, and a pair of revoluble shafts carried by said radiator casing and connected with said flexible member, said revoluble shafts being manually operable for the purpose of shifting said flexible member of textile fabric in 125 130

order to spread out in proximity to said openings other portions than said first mentioned portion of said flexible member of textile fabric.

- 5 4. A device of the character described, comprising a casing to be fitted over a radiator, said casing being provided with openings through which air, heated by the radiator and containing particles of dust and
10 smoke tends to make its escape, a plurality of supporting rods carried by said casing and extended through said casing, a cloth member engaging said supporting rods and partially supported thereby, said cloth member being suitable for arresting and holding particles of smoke and dust and being movable for the purpose of bringing different portions of said cloth member into proximity to said openings, and a pair of revolvable shafts journaled upon said casing and connected with said cloth member, for shift-

ing different portions thereof into proximity to said openings with which said casing is provided.

5. A device of the character described, comprising a radiator casing provided with means for facilitating the passage of air from the radiator out into the room, a flexible member made of textile fabric and carried by said radiator casing, said member of 30 textile fabric being so located that air in passing from the radiator out into the room passes through said member of textile fabric, and mechanism connected with said member of textile fabric and manually operable for 35 shifting said member of textile fabric into different positions relative to said radiator casing.

Signed at New York city, in the county of New York and State of New York, this 25th 40 day of November, 1925.

CHARLES KASPER VOLCKENING.
